UNITED STATES PATENT OFFICE.

JOHN ROYDEN PEIRCE, OF NEW YORK, N. Y.

POLISHING-MACHINE.

No. 817,798.

Specification of Letters Patent.

Patented April 17, 1906.

Application filed May 24, 1905. Serial No. 262,076.

To all whom it may concern:

Be it known that I, JOHN ROYDEN PEIRCE, a citizen of the United States, residing in the borough of Manhattan, city, county, and State of New York, have invented certain new and useful Improvements in Polishing-Machines, of which the following is a specification.

This invention aims to provide a machine for smoothing and polishing marble and similar stones and which automatically accomplishes all the operations required with the least expenditure of time and energy. A number of polishing-tools, generally three, are arranged to act in succession upon the marble, the materials and rate of rotation of these tools being so regulated that the marble passes a tool as soon as this tool has done all the work which it can efficiently do. Water is fed continuously and automatically to the faces of the tools to overcome the tendency to heating which would be due to a rapid operation of the machine. The tools are arranged close together, except for a space just in advance of the last tool where the marble may be cleaned before submitting it to the final polishing or mop disk.

Various other features of improvement are referred to in detail hereinafter, and the points of novelty set forth in the claims.

The accompanying drawings illustrate a machine embodying the invention and designed for continuously polishing baseboards and similar pieces of marble.

Figure 1 of the drawings is a side elevation. Fig. 2 is a plan. Fig. 3 is an end elevation, partly in cross-section. Fig. 4 is a vertical cross-section through the center of one of the tools. Fig. 5 is an under side view of the engaging device at the lower end of one of the shafts. Fig. 6 is a plan of one of the tools. Fig. 7 is an elevation thereof. Fig. 8 is a plan of a portion of a bed and a cleaning device.

Referring to the embodiment of the invention illustrated, A, B, and C are tools of suitable material for smoothing and polishing the face of the marble in successive steps. Below these tools the marble D is fed continuously on a thick canvas belt E, which runs around drums F at its ends, which drums are provided with worm-gears G, driven from a longitudinal driving-shaft H. The marble is guided by a pair of guides J, fastened on their supports by means of bolts passing through transverse slots, as shown, whereby

lateral adjustment of the guides may be effected to accommodate slabs of different widths. A number of rollers K are arranged immediately below the belt and as close together as possible, so as to take the weight of the stone and the pressure of the polishing-tools.

The tools are operated by means of vertical shafts L, M, and N, respectively, each of which is provided with a bevel-gear O at its upper end, and a common horizontal driving-shaft P is provided with bevel-gears Q, meshing with the gears O. The shaft P is mounted in bearings R and S, mounted upon the face of the frame of the machine, and the vertical shafts are provided with upper bearings T and lower bearings U, also mounted on the face of the frame.

In order that the work shall be perfectly done in one pass of the marble through the machine, the materials of the several wheels being determined, the rate of rotation of the tools should bear a fixed ratio to the rate of feed of the marble. The pressures on the different tools may be varied to compensate for differences in rapidity of action of different materials used for the several tools. For example, the machine shown is designed to produce a speed of three hundred revolutions per minute for the polishing-tools with a belt speed of one foot per minute. The fixity of relation between the two speeds is secured by connecting the driving-shaft P of the tools with the driving-shaft H of the belt, and in order to reduce the speed sufficiently this may be done by means of sprocket-chains V and W, connected, respectively, to sprocket-wheels on said driving-shafts, and each connected also to a sprocket-wheel of suitable diameter on an intermediate shaft X.

The frame of the machine preferably comprises transverse bars Y and Y', which carry at their front portions the longitudinal members Z, which support the guides J and the belt and connected parts. Upon the rear of the transverse members Y' is supported the frame for carrying the tools and which comprises a front plate a and side plates b, with horizontal stiffening-ribs c at the back of the front plate. The front plate is suitably curved to make room for the table and the vertical shaft and is provided with projecting portions d e, carrying the bearings for the several shafts. Certain improvements are also provided applicable to the individual

polishing-tools, and these will be understood more clearly from the specific examples shown in Figs. 4 to 7. Taking the shaft *L* as an example, it will be seen that it is hollow, and 5 water is fed thereto constantly from any suitable source of supply, such as the hose *f*, whose nozzle *g* enters the upper end of the shaft. A spiral spring *h* is provided bearing at its upper end against the under side of the 10 portion *d* of the frame and at its lower end against a collar *j* on the shaft, so as to hold the shaft and the tool down to their work and which is adjustable to vary the pressure. A universal or flexible joint *k* is provided 15 near the lower end of the shaft and is of any suitable design to permit the passage of the water. This flexible joint permits the tool to adapt itself to any large irregularities which may occur on the face of the marble without 20 interfering with the removal of the small irregularities, which is the function of the tool.

Preferably instead of the usual disk I use a tool *A* in the form of a ring. This permits the maintenance of a certain quantity of water at the center and at the same time practically eliminates the tendency to rock, which sometimes occurs in disks by reason of the slower wear at the center as compared with the edge. The present tool being in the 30 form of a ring of considerable diameter, the rate of rotation and of wear on all points of the face is substantially equal. Where the central opening of the ring is wider than the width of the marble, as illustrated, (see Fig. 35 4,) the inner edge *l* of the ring moves over as great or a slightly greater length of marble than the outer edge *m* in each revolution, and this construction should fully eliminate the ordinary tendency.

40 A special form of connection is provided between the polishing-tool and the lower end of the shaft, and this connection has been found of great value whether the tool be of disk or ring form or of any other form. This 45 is a toothed connection, of which the teeth may be of various forms. Preferably a disk or engaging device *k'* is connected to the lower end of the universal-joint member *k* and is provided with three radial teeth *n* at 50 the lower end to engage between corresponding teeth *o* on the polishing-ring *A*. There is no positive connection except in the horizontal plane of the teeth. Thus rotation is transmitted; but otherwise the tool is entirely free from the shaft. This connection permits an instantaneous removal or replacement of a polishing-tool by merely slightly lifting the shaft.

For removing the marble-dust and water 60 before the stone reaches the mop-disk *C* a space is left between the two disks *B* and *C*. Preferably the cleaning is effected by means of one or more water-jets and rubber scrapers, and these may be conveniently supported in 65 the manner indicated in Fig. 8, being adapt-

ed for easy removal and replacement, especially for cleaning the scrapers. Through the flange *p* at the front of the table there are provided pairs of slots *q* and *r*, and in the rear flange *s* there are provided single slots *t*. 70 Each set of slots *q*, *r*, and *t* serves to hold a nozzle *u* and a scraper *v*, the latter being, for example, of rubber backed with wood to stiffen it. Two nozzles and two scrapers, as illustrated, will ordinarily be sufficient. It 75 will be understood that jets from the nozzles *u* soften and wash off to a considerable extent the marble-dust, and the scrapers easily remove what is not washed off by the nozzles.

The compositions of the several tools will 80 vary in accordance with the character of the work to be done. For cheap work the marble may be brought directly from the saw to the polishing-machine, in which case the tool *A* may be of carborundum of about eighty 85 grit or eighty mesh, the second tool of a mixture of carborundum of the two grades known as "220" and "3 F powder," the third tool *C* being a mop or felt disk or ring used with ordinary polishing-powders. Little or no 90 water is used with the mop *C*, the stone being already damp and generally sufficiently damp for polishing. For fine work requiring a high polish the marble will be first "rubbed" to remove the marks of the saws. In such 95 case the present machine becomes a polishing-machine more than a grinding-machine, and I have found that for the first two tools a material known as "alundum" (which is supposed to be an electric-furnace product 100 analogous to carborundum, a silicate of aluminium) of one-hundred grit and two-hundred grit, respectively, is satisfactory.

The use of the specific compositions described is not claimed in the present application; but I am not to be understood as thereby waiving my right to claim the same in a 105 separate application.

Though I have described with great particularity of detail a specific machine embodying the invention, yet it is not to be understood therefrom that the invention is limited to the specific embodiment illustrated.

Various modifications thereof in detail and in the arrangement and combination of the 115 parts may be made by those skilled in the art without departure from the invention.

What I claim is—

1. A polishing-machine for marble and similar stones, including in combination successive tools for smoothing and polishing the face of the marble in successive steps, vertical shafts for said tools and provided with beveled pinions *O*, a horizontal driving-shaft *P* provided with beveled pinions *Q* engaging 120 the pinions on said vertical shafts, a belt *E* for feeding the marble to said tools, a driving-shaft *H* for driving said belt, and a connection between said driving-shafts whereby 125 a fixed relation is maintained between the 130

rate of rotation of the tools and the rate of feed of the marble.

2. A polishing - machine for marble and similar stones, including in combination successive tools for smoothing and polishing the face of the marble in successive steps, vertical shafts for said tools, a belt for feeding the marble to said tools, transverse members Y Y' carrying at the front the belt and connected parts, and a frame carried upon the rear of said transverse members and provided with bearings for said shafts projecting over said belt.

3. A polishing - machine for marble and similar stones, including in combination successive tools for smoothing and polishing the face of the marble in successive steps, vertical shafts for said tools, a belt for feeding the marble to said tools, longitudinal members Z carrying said belt, guides J carried at the sides of said belt by said members Z, and a frame at the rear provided with bearings for said shafts projecting over said belt.

4. A polishing - machine for marble and similar stones, including in combination successive tools for smoothing and polishing the face of the marble in successive steps, vertical shafts for said tools, a belt for feeding the marble to said tools, a frame at the rear pro-

vided with bearings for said shafts projecting over said belt, and a spring pressing each of said shafts downward, said shafts being flexibly connected to said tools.

5. A polishing - machine for marble and similar stones, including in combination successive tools for smoothing and polishing the face of the marble in successive steps, and means between two such tools for cleaning the face of the marble.

6. A polishing - machine for marble and similar stones, including in combination successive tools for smoothing and polishing the face of the marble in successive steps, and cleaning means between two such tools and comprising a water-nozzle and a scraper.

7. A polishing - machine for marble and similar stones, including in combination a polishing-tool, and a shaft having a toothed engagement at its lower end with the tool for rotating the same.

In witness whereof I have hereunto signed my name in the presence of two subscribing witnesses.

JOHN ROYDEN PEIRCE.
